HANDLE LEVER OPERATED POWER
MULTIPLYING HAND BRAKEGeorge E. Dath, Mokena, Ill., assignor to W. H.
Miner, Inc., Chicago, Ill., a corporation of Dela-
ware

Application June 19, 1947, Serial No. 755,641

2 Claims. (CL. 74—505)

1

This invention relates to improvements in hand brakes of the lever operated type, especially adapted for use on railway cars.

One object of the invention is to provide a hand brake mechanism comprising a chain tightening drum, rotated by a swinging operating handle lever to apply the brakes, wherein the drum is held against rotation in brake releasing direction through the medium of a locking dog and the actuating lever is automatically disconnected from operative relation with respect to the drum when dropped to pendant position to thereby allow rotation of the drum independently of the operating handle lever when the dog is disengaged to effect release of the brakes.

A more specific object of the invention is to provide in a hand brake mechanism of the character indicated, a mechanism for rotating the drum, comprising a ratchet wheel rotatable with the drum, a swinging lever for rotating the ratchet wheel, a sliding spring pressed pawl on the lever engageable with the ratchet wheel to lock the lever to the ratchet wheel and effect rotation thereof, and a trip element for the pawl, engageable with a fixed stop when the lever is dropped to pendant position to retract the pawl and release the lever from operative engagement with the ratchet wheel, thereby permitting rotation of the drum independently of the operating lever.

Other objects of the invention will more clearly appear from the description and claims herein-after following.

In the accompanying drawings forming a part of this specification, Figure 1 is a side elevational view of a lever operated hand brake mechanism embodying my improvements, showing the mechanism mounted on the end wall member of a railway car. Figure 2 is a view, similar to Figure 1, with the operating handle lever mechanism and the cover plate of the brake housing removed. Figure 3 is a view, similar to Figure 2, partly broken away, showing the locking dog in released position. Figure 4 is a side elevational view of the improved lever operated hand brake mechanism shown in Figure 1, looking at the opposite side of the mechanism. Figure 5 is a transverse, vertical sectional view, corresponding substantially to the line 5—5 of Figure 4. Figure 6 is a vertical sectional view of the lever mechanism of the improved brake, corresponding substantially to the line 6—6 of Figure 5.

In said drawing, 10 indicates a portion of the vertical end wall of a railway car on which my

2

improved hand brake mechanism, contained in housing 11, is mounted.

My improved hand brake mechanism, as illustrated in the drawings, comprises broadly a chain winding drum A, a gear wheel or spur gear B rotatable with the drum; a driving pinion C meshing with the gear wheel B, a ratchet wheel D rotatable with the pinion, a locking dog E for the ratchet wheel, a second ratchet wheel F rotatable with the pinion C and ratchet wheel D, a swinging operating handle lever G, a spring actuated sliding pawl H on the lever G engageable with the ratchet wheel F, and a trip element J on the operating lever G for the pawl H.

The housing 11, within which the operating parts of the brake mechanism are contained, comprises a vertically disposed rear wall 12, laterally spaced, vertical side walls 13 and 14, top and bottom walls 15 and 16, and a curved front wall 17. The side wall 14 is in the form of a removable cover plate secured by screws 18 extending into webs formed on the housing proper. The housing is divided into two chambers 19 and 20 by a transverse, vertically disposed partition wall 21. The portion of the bottom wall 16, at the chamber 19 of the housing, is upwardly offset with respect to the portion thereof which closes the bottom of the chamber 20, and said offset wall portion is provided with spaced openings 22—22 therethrough, adapted to accommodate the vertically extending portions of the usual brake chain, which chain is indicated by 23. The rear wall 12 of the housing has securing ears 24—24 extending therefrom by which the housing is supported on the end wall 10 of the car, the same being fixed to the end wall by bolts 25—25 extending through the ears.

The chain winding drum A is mounted in the chamber 19 and has the gear wheel or spur gear B cast integral therewith. The casting, comprising the combined drum and spur gear, is rotatably supported at one end by an integral axial shaft 26, journaled in a bearing opening 27 provided in the cover plate or wall 14 of the housing, and at the other end by an inwardly projecting bearing boss 28 on the wall 13 engaged in a suitable axial bearing opening of the drum. The drum A is of the pocketed type, acting in the manner of a sprocket wheel, and has the chain 23, which leads to the brake mechanism proper of the car, trained thereover in the usual manner. The end of the chain which leads to the brake mechanism proper is indicated by 29 and the free weighted end thereof is indicated by 30. The drum has peripheral, annular guide flanges

31—31 at opposite sides thereof, the flange 31 at the spur gear side of the drum being accommodated in an opening 32 in the partition wall 21 of the housing, which opening also serves as bearing means for said flange. The spur gear wheel B of the combined drum and gear casting is located in the chamber 20 of the housing and meshes with the driving pinion C, which is fixed to a shaft 33, supported at opposite ends thereof in a bearing seat 34 and a bearing opening 35 provided respectively in the opposite side walls of the bottom portion of the chamber 20, the shaft extending through the opening 35 which is provided in the side wall or cover plate 14 of the housing and projecting outwardly of said wall. The shaft 33 carries the ratchet wheel D, which is fixed thereto, this ratchet wheel being arranged on the shaft between the pinion C and the wall 14 of the housing. The projecting end of the shaft is threaded at its extremity to receive a locking nut 36, and is of square cross section inwardly of said threaded end, as indicated at 37. The ratchet wheel F is mounted on the square section 37 of the shaft, this ratchet wheel being provided with an axial opening of square cross section within which the square portion of the shaft tightly fits, the ratchet wheel F being thus locked to the shaft for rotation therewith.

The locking dog E, which serves to lock the brake mechanism against release, is pivoted on an inwardly projecting lug 38 on the rear wall 12 of the housing and has a depending arm 39 provided with a tooth 40 at its outer end engaging the ratchet wheel D. At the inner or upper end, that is, at the pivoted portion thereof, the dog has a laterally extending, radially projecting lug or tail 41 thereon, which is engaged by a trip lever 42 by which the dog is operated. The trip lever 42 is rotatably journaled at its lower end on the shaft 26, being located between the spur gear B and the side wall 14 of the housing. The upper end of the lever 42 is laterally offset and extends through an opening or slot 43 provided by cutting out the upper section of the cover plate or wall 14 of the housing, the outer end of said lever being in the form of a hand grip portion 44. The lower or pivoted end of the lever 42 is provided with spaced lugs 45 and 46 adapted to engage opposite sides of the lug 41 of the dog E to swing the same into and out of engagement with the ratchet wheel as the lever is swung to and fro. A coil spring 47, interposed between the lower end portion of the arm 39 of the dog and the wall 12 of the housing, serves to press the dog yieldingly against the ratchet wheel.

The operating handle lever G is swingingly supported on the shaft 33 exteriorly of the housing 11, the same comprising a hollow head portion 48 engaged over the ratchet wheel F and an operating lever arm 49 extending radially from the head portion. The head portion 48, which is engaged over the ratchet wheel, is open at its inner side, as indicated at 50, the opening 50 being circular in outline and having the wall thereof grooved to provide an annular bearing seat 51, which is engaged over an outwardly projecting, annular flange 52 on the ratchet wheel F at the inner side thereof, thereby supporting the head for rotation on said ratchet wheel. The closed side of the head 48 is provided with a bearing opening 53, through which the shaft 33 extends, the head being thus also rotatably supported at its outer side by the shaft.

At the headed end thereof, the arm 49 of the

lever G is provided with a lengthwise extending opening or seat 54 of substantially rectangular cross section, within which the pawl H is slidably mounted, the latter being of rectangular cross section to fit the opening and prevent turning of the pawl. The pawl H is yieldingly forced toward the ratchet wheel F by a coil spring 55 interposed between the inner end of the pawl and the bottom wall of the seat 54. At the outer end, the pawl has a tooth 56 engaging with the ratchet wheel F, the inclination of the teeth of the ratchet wheel and pawl being such that the teeth lock when the lever G is swung to the left, as viewed in Figures 1 and 6, to turn the ratchet wheel, and have ratcheting action when the lever swings to the right, thus effecting intermittent rotation of the ratchet wheel F when the lever is oscillated.

To retract the pawl H from operative engagement with the ratchet wheel F, when the operating lever G is dropped to pendant position, the trip element J is provided. This element is in the form of a bell crank lever pivoted on a pin 57 extending through the same, and laterally extending, spaced flanges 58—58 on the lever arm 49, adjacent the head 48. The bell crank lever-like trip element J has two radially extending arms 59 and 60, which are at right angles to each other, the arm 60 engaging with a laterally projecting lug 61 at the inner end of the pawl H, which projects through a slot or opening 62 communicating with the opening between the flanges 58—58, into the path of movement of the arm 60. The arm 59 is engageable with a fixed projection or stop lug 63, provided on the side wall or cover plate 14 of the housing when the handle lever G is dropped to pendant position.

In the operation of my improved mechanism, 40 in applying the brakes, the operating handle lever G is oscillated, thereby effecting intermittent rotation of the ratchet wheel F and intermittent rotation of the drum A in clockwise direction, as viewed in Figure 4, through the medium of the power multiplying pinion and gear connection. 45 During this action, the dog E holds the ratchet wheel D against rotation in chain unwinding direction, ratcheting over the ratchet wheel D. When the operator releases his hold from the operating lever G, the latter drops to its pendant position through action of gravity and the pawl H is automatically retracted from operative engaged position with the ratchet wheel F by the trip lever G, the arm 59 of which strikes against the stop lug 63, as seen in Figure 1. With the pawl H thus disengaged, the drum is free to rotate when the brakes are released by retracting the dog E from operative engagement with the ratchet wheel D by means of the lever 44, the spur gear B and the pinion C, together with the ratchet wheel F, being free to rotate with the drum without effecting any movement of the disconnected operating handle lever G.

I claim:

1. In an operating handle lever mechanism for a hand brake, comprising a chain winding drum rotatable about a horizontal axis, and a ratchet wheel operatively connected to the drum for rotation therewith, the combination with a swing operating lever, said lever being swingable to and from pendant position about the axis of said ratchet wheel; a spring pressed sliding pawl on said lever engageable with said ratchet wheel; a bell crank pivoted on said lever for swinging movement on an axis parallel to the axis of swing 65 movement of said lever and having a pair

of arms, one of which has shouldered engagement with the pawl; and a fixed stop in the path of movement of the other arm of said bell crank to be engaged thereby and rotate the bell crank when the operating lever is dropped to pendant position, thereby retracting said pawl from operative engagement with the ratchet wheel.

2. In an operating lever mechanism for a hand brake including a rotary chain winding element, a ratchet wheel operatively connected with said element for rotation therewith, the combination with an oscillatory operating lever swingable about a horizontal axis, said lever being movable to pendant position; a spring pressed sliding pawl on said lever engageable with said ratchet wheel to effect intermittent rotation of said wheel when the lever is oscillated in reverse directions; a laterally projecting lug on said pawl; a bell crank for retracting said pawl, said bell crank being rotatably mounted for swinging movement on said lever on an axis parallel to the axis of swinging movement of said operating lever, said bell crank

having radially extending arms at right angles to each other, one of which has shouldered engagement with the lug of the pawl to retract said pawl; and a fixed stop in the path of movement of the other of said arms to be engaged thereby when the operating lever is dropped to pendant position, thereby rotating said bell crank to disengage the pawl from the cooperating ratchet wheel.
